SHELVING STRUCTURE

Filed Sept. 22, 1924

Patented May 29, 1928.

UNITED STATES PATENT OFFICE.

ALBERT M. WOLTZ, OF BALTIMORE, MARYLAND, ASSIGNOR, BY MESNE ASSIGNMENTS,
TO GRAND RAPIDS STORE EQUIPMENT CORPORATION, OF GRAND RAPIDS, MICHIGAN.

SHELVING STRUCTURE.

Application filed September 22, 1924. Serial No. 739,112.

This invention is a shelving structure of the type in which a plurality of shelves are arranged in a vertical stack.

One of the objects of the invention is to provide standardized component elements, which may be readily and quickly constructed into a stack of shelving for store, or any other desired use. A further object is to provide means for so connecting the shelves with standardized sectional end wall elements, as to provide a rigid end wall structure. A further object is to provide means for locking the shelves in vertical alignment and at the same time bracing the stack. A further object is to provide means for maintaining the two end walls of a stack in rigid parallel relation, in a manner to prevent lateral separation thereof.

The invention will be hereinafter fully set forth and particularly pointed out in the claims.

In the accompanying drawing:—

Figure 1 is a perspective view illustrating a stack of shelving construction in accordance with the invention. Figure 2 is a detail perspective view illustrating the method of assembling the component parts. Figure 3 is a detail horizontal sectional view illustrating contiguous ends of adjacent stacks. Figure 4 is a detail front elevation illustrating the method of engaging the end pieces and the shelves. Figure 5 is a detail rear elevation illustrating the method of bracing the stack.

Referring to the drawing, A designates a stack of shelving consisting of a base 10, a top piece 11, and a plurality of shelves 12, held in superposed spaced relation by end pieces or spacers 13. The base 10 and top piece 11 may, if desired, be of the well-known unit type of construction.

Each shelf is provided with oppositely disposed sets of grooves 14 in the top and bottom surfaces respectively, and contiguous to the ends of the shelf. These grooves form seats for the upper and lower edges respectively, of the end pieces or spacers 13, providing in effect, a tongue and groove engagement which is sufficiently snug to hold the parts together with substantial rigidity. The lowermost grooves of the lowest shelf 12, are engaged by the top edges of the end pieces of the bottom section 10, and in like manner the topmost grooves of the highest

shelf 12 are engaged by the lower edges of the end walls of the top section 11.

Those portions of the ends of the shelves which project beyond the planes of the end walls formed by the end sections 13, are provided with aligned recesses 16, so as to provide interlocking seats for aligning strips 17, which extend the full length of each end wall of the shelving structure. The strips 17 may be secured against displacement by means of screws 18, as shown. To prevent lateral spreading of the end walls stop strips 19 are provided, said strips being of approximately the same length as the shelves. Each stop strip 19 is secured at each end to a shelf 12 by means of screws 20, and to the contiguous end pieces 13 which are directly engaged with the said shelf, by screws or similar fastenings 21. These stop strips project slightly above and below the planes of the respective shelves to which they are secured, so as to provide stops for limiting rearward movement of articles placed upon the shelves. This is of particular importance where the shelving is used for the storage and display of shoe boxes.

In practice, if the shelving structure consists of a single stack, the end walls are covered by suitable finished cover-walls, provided with end pilasters 22. If two or more stacks are to be arranged in alignment, they are placed end to end, with the contiguous ends of adjacent stacks slightly separated. The space between any two stacks is covered by a pilaster 25, provided with a projecting portion 26, extending into the space, the contiguous corners of the shelves 12 being cut away as indicated at 27, to provide the necessary clearance. The pilaster may be held in place in any suitable manner.

The advantages of the invention will be readily understood by those skilled in the art to which it belongs. For instance it is obvious that the shelves 12, end wall sections 13, aligning strips 17 and stop strips 19 may all be made of predetermined standard sizes, and in large quantities ready to be assembled at will. When desired, a stack of shelves of any desired height may be quickly assembled, by interengaging the necessary number of end wall sections 13 with the grooves 14 of the desired number of shelves. In this manner the main shelving structure may be quickly erected, after which the

aligning strips 17 may be readily secured in position so as to lock the shelves in vertical alignment. The time required to then place the stop strips 19 in place is very short, and the entire structure may be set up with the expenditure of a minimum of time and labor, ready to be shipped to the place where it is to be installed. By interlocking the end wall sections and the shelves, a very rigid structure is provided, and by employing the aligning strips 17 relative forward and backward movement of the shelves is prevented. If further stiffening is desired, it is provided by the strips 19, which are anchored to the shelves and the end pieces; thereby preventing relative lateral movement of the end walls. The structure thus provided is very rigid and more than capable of withstanding all of the strains to which shelving of this kind is normally subjected.

Having thus explained the nature of the invention and described an operative manner of constructing and using the same, although without attempting to set forth all of the forms in which it may be made, or all of the forms of its use, what is claimed is:—

1. A shelving structure of the character described comprising a plurality of shelves having aligned recesses in their ends, sectional end wall units engaging the respective shelves and maintaining them in spaced relation, shelf aligning strips seated in the aligned recesses of the shelves, and means cooperating with said shelves for holding the end wall units against lateral movement with relation to each other.

2. A shelving structure of the character described comprising a plurality of shelves having aligned recesses in their ends, sectional end wall units engaging the respective shelves and maintaining them in spaced relation, shelf aligning strips seated in the recesses of the shelves, and stop strips, each stop strip being secured to one edge of a shelf and also secured at its ends to the end wall units contiguous to said shelf.

3. A shelving structure of the character described comprising a plurality of shelves having top and bottom grooves near their ends, sectional end wall units having their edges seated in the grooves of the respective shelves, whereby the end edges of said shelves project beyond the respective vertical planes of said wall units, means coop-

erating with said shelves holding said end units against lateral movement with relation to each other, and shelf aligning means engaging the projecting end edges of the shelves outside of the end wall units.

4. A shelving structure comprising a plurality of stacks of shelves, each stack comprising a plurality of shelves, end units engaging said shelves of each stack in positions spaced from the end edges thereof, means engaging said end edges for bracing the shelves and pilasters covering the spaces between the respective stacks and having portions extended into the space between contiguous ends of adjacent shelves, the corners of the shelves being cut away to provide clearance for said pilasters.

5. A shelving structure comprising a plurality of stacks of shelves arranged in alignment, each stack consisting of a plurality of shelves united by sectional end wall units, the end edges of said shelves projecting beyond the respective vertical planes of said end wall units, whereby spaces are provided between end walls of adjacent stacks, said end edges having recesses therein, aligning strips engaging said recesses, and pilasters having portions extending into the spaces between the stacks, the forward corners of the shelves being cut away to provide clearance for said extended portions.

6. A shelving structure of the character described comprising a plurality of shelves, sectional end wall units engaging the top and bottom faces of said shelves, the ends of said shelves projecting beyond the planes of said end wall units, and aligning strips, the projecting ends of said shelves having complementary portions interlocking with said strips.

7. A shelving structure of the character described comprising a plurality of shelves provided with top and bottom grooves near their ends, and recesses in their end edges, sectional end wall units having their edges engaging the grooves so that the shelves are maintained in superposed spaced relation with their ends projecting beyond the respective vertical planes of said wall units, and aligning strips engaging the said recesses.

In testimony whereof I have hereunto set my hand.

ALBERT M. WOLTZ.
